UNITED STATES PATENT OFFICE

GEORGE T. HORTON, OF CHICAGO, ILLINOIS

STORAGE TANK

Application filed May 25, 1928. Serial No. 280,509.

This invention relates to improvements in floating roofs for liquid storage tanks, and more especially to a roof for a tank for the storage of volatile oils in which the roof floats 5 on the liquid to lessen evaporation.

One of the features of my invention is the provision of improved means for permitting the roof to float upwardly and downwardly and at the same time maintain a seal to lessen 10 or eliminate evaporation of liquid at the periphery of the tank.

Another feature of my invention is the provision of means for insulating the wall of the tank.

Other features and advantages of my invention will appear more fully as I proceed with my specification.

In that form of device embodying the features of my invention shown in the accompanying drawings, Fig. 1 is a vertical sectional view and Fig. 2 is a similar fragmentary view on an enlarged scale.

As shown in the drawings, the tank includes a shell with a vertical wall or walls 10 made of sheet metal or other suitable material 25 and having a bottom 11. The tank is preferably cylindrical, although it is obvious that it may be square, rectangular, polygonal, or any other desired shape. Hereafter, in the 30 specification, I shall describe the device as if cylindrical.

12 indicates in general the floating roof which floats on the oil 13, or other liquid stored in the tank and moves upwardly and 35 downwardly vertically in accordance with the volume of oil in the tank. 14 indicates a cylindrical curtain concentrically supported inside of the shell and spaced therefrom to leave an annular space 15 between the wall of the shell and the curtain surrounding the tank. The curtain may be made of any suitable material and should have a certain amount of flexibility and resiliency. For example, the same may be made out of relatively thin sheet steel.

The roof 12 may be of any suitable construction adapted to float on the oil 13. I have here shown the same as comprising a circular pontoon 12^a carrying at its upper inner edge the diaphragm or crown sheet 12^b. 50 This crown sheet I have here shown as made with some fullness so that the same may flex upwardly and downwardly in accordance with changes in the volume in the vapor space 13^a above the oil and inside of the pontoon. In Fig. 1 the diaphragm 12^b is shown in its upper position in broken lines and in its lower position in solid lines.

Any suitable means may be provided for making a seal between the edge of the floating roof and the curtain 14. There are different forms of such seals well known in the art and anyone of the same may be used. Merely for example, I have here shown such a seal as consisting of a flexible tubular member 16 which is adapted to conform in thickness more or less to the space between the edge of the roof and the curtain 14. With any kind of seal that is used, however, there is more or less difficulty experienced in keeping 70 the joint between the roof and the wall of the tank perfectly sealed. If the material used for the seal is too soft and compressible the same deteriorates and does not wear well. If stiff material is used, such as metal shoes, 75 there is more or less difficulty experienced in keeping the same in contact with the wall of the tank throughout the periphery of the roof. Where the seal is directly against the wall of the tank, it will be seen that since the tank 80 wall is made of relatively heavy and stiff material it is difficult to make the same smooth. It is also impossible to make such tank wall change in shape to conform at all times to the shape of the roof during its vertical movements. One of the principal features of my 85 invention is to overcome the defects just noted and to provide an improved reliable seal. This is accomplished by providing the curtain 14 which is made of relatively thin flexi- 90 95

ble material. It is relatively easy to make a good seal between the periphery of the roof and such a curtain. Such a curtain being of thin material, may be made much smoother than the wall of the tank and it will also 5 change its shape and conform to the shape of the roof during its movements.

The space 15 between the curtain 14 and the wall of the tank 10 is filled with some suitable liquid, for example, water or brine, preferably heavier than the oil stored in the tank, and the bottom of the curtain 14 is provided with some ports 14^a to afford communication between the space 15 and the bottom of 15 the tank. By providing the water or other liquid 17 in the space 15, the pressure on both sides of the curtain 14 is equalized thus permitting the use of a relatively thin flexible material for such curtain. In using water 17 or other liquid heavier than the oil 13, there 20 is also provided a liquid seal so that oil does not enter in the space 15 and consequently the same is not exposed to the atmosphere in this space. There are preferably provided ports 25 18 at the top of the space 15 opening to the atmosphere.

The curtain 14 may be supported in any suitable manner. I have here shown the same as hanging from a channel iron 19 attached 30 to the inner edge of the tank wall 10. The lower edge of the curtain 14 is preferably attached to the bottom of the tank as by means of an angle iron 20.

It will be noted that the liquid 17 in the 35 space 15 and the double wall of the tank afforded by the shell 10 and the curtain 14 serve to insulate the tank.

While I have shown and described certain embodiments of my invention, it is to be understood that it is capable of many modifications. Changes, therefore, in the construction and arrangement may be made without departing from the spirit and scope of the invention disclosed in the appended claims, in 45 which it is my intention to claim all novelty in my invention as broadly as possible in view of the prior art.

What I claim as new, and desire to secure by Letters Patent, is:

50 1. A storage tank including; an outer shell; a yieldable inner shell of relatively light sheet metal spaced therefrom and extending substantially to the tank bottom; a fluid passage between the space bounded by the inner shell and the space between the shells to equalize the pressure on both sides of the inner shell; and a roof having a sealing contact with the inner shell adapted to float upon liquid therein.

55 2. A storage tank as claimed in claim 1, having a sealing liquid in the space between the shells.

3. A storage tank as claimed in claim 1, in which the inner shell has its lower edge attached to the tank bottom.

4. A storage tank as claimed in claim 1, having sealing liquid in the space between the shells, said liquid being heavier than the liquid for the storage of which the tank is 70 designed.

5. A storage tank as claimed in claim 1, in which the fluid passage includes a port through the inner shell.

In witness whereof, I have hereunto set my hand this 23 day of May, 1928.

GEORGE T. HORTON.
